INVENTOR

UNITED STATES PATENT OFFICE.

JOHN SPERLING, OF CLEVELAND, OHIO.

ICE-CREEPER.

1,047,716.

Specification of Letters Patent.

Patented Dec. 17, 1912.

Application filed July 8, 1912. Serial No. 708,221.

To all whom it may concern:

Be it known that I, JOHN SPERLING, a citizen of the United States of America, residing at Cleveland, in the county of Cuyahoga and State of Ohio, have invented certain new and useful Improvements in Ice-Creepers, of which the following is a specification, reference being had therein to the accompanying drawing.

10 This invention relates to an ice creeper, and the primary object of my invention is to furnish the heel of a shoe with a novel device that will prevent a person from slipping and falling upon ice or smooth surfaces.

15 Another object of this invention is to provide an ice creeper that can be permanently worn upon the heel of a shoe and when not in use swung to an inactive position that 20 prevents the ice creeper from injuring the surface of a floor or tearing a carpet.

25 A further object of this invention is to provide an ice creeper that is practically invisible when attached to the heel of a shoe and the manner of attaching the same to a heel does not unduly mar or injure the heel.

30 A still further object of this invention is to provide an ice creeper consisting of comparatively few parts that are easily and quickly assembled to provide a durable and efficient structure for the purposes for which it is intended.

35 With the above and other objects in view, the invention resides in a novel construction, combination and arrangement of parts to be hereinafter specifically described and then claimed.

Reference will now be had to the drawing, wherein:—

40 Figure 1 is a side elevation of the ice creeper as applied to the heel of a shoe, showing the creeper in an inactive position. Fig. 2 is a longitudinal sectional view of the same, showing in dotted lines the ice creeper in position for use. Fig. 3 is a bottom plan of the ice creeper in the position shown in Fig. 1. Fig. 4 is a perspective view of the detached heel strap, and Fig. 5 is a perspective view of the creeper plate.

45 Further describing my invention with reference to the drawing wherein like numerals denote corresponding parts throughout; 1 denotes the heel of a shoe 2 and secured to the sides of the heel 1 by screws 3 or other fastening means are curved straps 4. The forward ends of said straps are bent

inwardly, as at 5 at the front wall 6 of the heel, said straps terminating in apertured oppositely disposed bearings 7.

8 denotes a rod arranged in the bearings 7 and having the ends thereof reduced to provide screw threaded shanks 9 upon which are screwed nuts 10 for retaining the rod 8 in said bearings. The rod 8 is stationary within the bearings 7 and the top and bottom sides of said rod are provided with flat surfaces 11.

12 denotes a creeper plate that has the rear edges thereof slotted at the sides, as at 13 and the slotted portions of said plate bent 70 to provide apertured lugs 14. The apertured lugs 14 are oppositely disposed and at right angles to the creeper plate 12, and said lugs are loosely mounted upon the rod 8, as best shown in Fig. 3. The creeper plate 12 75 has one side thereof provided with prongs 15 and these prongs are in the form of rivets whereby they can be easily and permanently secured to the creeper plate. The other side of the creeper plate 12 is provided with a flat spring 16, said spring having one end thereof riveted or otherwise connected to the plate, as at 17. The opposite end of the spring 16 engages one of the flat faces 11 of the rod 8, as best shown in Fig. 2. 80 The spring 16 serves to hold the creeper plate in an adjusted position, either in an inactive position beneath the arch of the shoe sole, as shown by full lines in Fig. 2 or in an active position as shown by dotted lines 90 in Fig. 2, the latter position of the plate being beneath the heel 1, with the prongs 15 depending to engage in a smooth surface and prevent the person from slipping and falling.

95 It is thought that the utility of the ice creeper will be apparent without further description, and while in the drawing there is illustrated a preferred embodiment of the invention, it is to be understood that the structural elements are susceptible to such changes as fall within the scope of the appended claim.

What I claim is:—

An ice creeper comprising a pair of heel 105 straps adapted to be secured to the sides of the heel and each having an angle-shaped forward portion abutting against and projecting forwardly from the front of the heel, the forwardly projecting part of each 110 angle-shaped portion being inset with respect to one side of the heel and forming a

bearing, a rod having cylindrical ends journaled in and projecting from said bearings and further having flat faces, means mounted upon the cylindrical ends of the rod for connecting it to said bearings, an adjustable creeper plate having one end thereof reduced and provided with apertured lugs positioned between the forwardly extending parts of said angle-shaped bearings and mounted upon the cylindrical ends of said

rod, and a flat spring fixedly secured to said plate and having an offset end engaging one of the flat faces of said rod for retaining the creeper plate in an adjusted position.

In testimony whereof I affix my signature 15 in the presence of two witnesses.

JOHN SPERLING.
